CLAIM

The ornamental design for a disassemblable rain barrel as shown and described.

DESCRIPTION

FIG. 1 is a front elevational view of a disassemblable rain barrel showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a rear, top and left side perspective view thereof;

FIG. 8 is a front, bottom and right side perspective view thereof;

FIG. 9 is a rear, top and left side perspective view showing the disassemblable rain barrel in a disassembled state;

FIG. 10 is an enlarged view of portion 10 in FIG. 7; and,

FIG. 11 is an enlarged view of portion 11 in FIG. 7.

The broken lines in the drawings illustrate portions of the disassemblable rain barrel which form no part of the claimed design.

The dot-dot-dash broken lines in FIGS. 7, 10, and 11 depict the boundaries of the detail enlargements that form no part of the claimed design.
